UNITED STATES PATENT OFFICE.

WILLIAM TERRY AND FESTUS RAWNSLEY, OF BRADFORD, ENGLAND.

LOOM FOR WEAVING PILE FABRICS.

SPECIFICATION forming part of Letters Patent No. 471,835, dated March 29, 1892.

Application filed September 8, 1891. Serial No. 405,102. (No model.)

To all whom it may concern:

Be it known that we, WILLIAM TERRY and FESTUS RAWNSLEY, both citizens of Great Britain, residing at Bradford, in the county 5 of York, England, have invented certain new and useful Improvements in Looms for Weaving Pile Fabrics; and we do hereby declare the following to be a full, clear, and exact description of the invention, such as will enable 10 others skilled in the art to which it appertains to make and use the same.

Our invention has reference to looms, which we propose to adapt by a new form of apparatus for the purpose of weaving looped pile 15 fabrics, such as hearth-rugs, door-mats, imitation-skin rugs, and other like fabrics.

In carrying out our invention we employ warp and weft of cotton or suitable material for forming the back of the fabric, while the 20 pile of the fabric may be composed of a warp of worsted or other suitable material. We also mount a suitable number of blades or other form of instruments upon a shaft situated behind the sleigh or going part of the loom 25 but independent of it, such blades passing through the reed, a dent of which may be removed to permit this to be done. These blades are triangular in shape and are arranged at suitable distances apart upon the 30 shaft which carries them, and upon the shed being formed the shuttle is sent across the loom, passing under the triangular-shaped blades and through the shed, after which the healds which operate the pile warp or one or 35 more combs are made to move laterally by cams, spiral springs, or other contrivances, so as to carry a thread of the pile warp over or across the top of each blade, after which the shed is closed, carrying the warp down over 40 the knife, forming a loop thereby, which is afterward secured into the fabric by the weft and the beating up of the sleigh in any well-known manner.

In order that our invention may be better 45 understood, we will now proceed to describe the same more fully, and for that purpose make reference to the accompanying drawings, illustrative thereof, wherein—

Figure 1 is an end elevation, partly in section, of a power-loom having our improvements applied thereto. Fig. 2 is a cross-section thereof, and Fig. 3 is a front elevation of

some of the parts shown in Fig. 2. Figs. 4 and 5 show in detail two views of portions of the combs O and the knives for forming the 55 loops.

A represents the frame-work of the loom; B, the crank-shaft; C, the sleigh-board carried upon the upper ends of the lathe-swords. The warp for forming the back of the fabric comes 60 off the beam F, while the warp for forming the pile of the fabric is supplied by the bobbins G, passing around drum G' and under rod G², carried by lever-arms G³, mounted on shaft 2, one at each side of the loom. The 65 said lever-arms are operated by the lever G⁴, also secured on the shaft 2. A rod G⁴¹ is pivoted to the lower end of the lever G⁴ and to the upper end of a lever G⁴², pivoted on a pin 4, projecting from the frame A. The lever 70 G⁴² carries a roller 5, which is operated by a cam 6. (Shown in heavy dotted lines and mounted on the shaft R⁴.)

H represents the breast-beam, and I the taking-up roller. Behind the sleigh-board is a 75 horizontal rod J, supported by brackets J', bolted to the frame-work A, upon which rod J are mounted any suitable number of triangular-shaped plates or blades K, the forward points of which pass through or between the 80 dents of the reed L, the said plates being secured on rod J by a key or other means, washers of suitable thickness being employed to separate each blade and the whole series of blades being kept together and tightened 85 up by nuts J². (See Fig. 3.)

In front of the heald-shafts M is a horizontal bar N, to which is attached a small grate or comb O, between the prongs or spaces of which each thread of the pile-forming warp 90 enters, as shown clearly in front view, Figs. 3 and 4. The pile-forming warp, which is governed by heald M', is made to enter between the prongs of the said comb at every pick or every alternate pick or every third 95 pick or otherwise, according as the pile is required to be fine or coarse, this being determined by a box-cam 7 on shaft R⁴, which cam, at one part of its revolution, lifts the heald M' a little distance above the other healds 100 and thus places the pile-warp into the teeth of the comb O. The box-cam 7 operates a roller 8, carried by the lever 9. One end 10 of the lever 9 is adapted to operate the heald M' and

the other end is pivoted to the frame A. One thread of warp also lies in the space between each two adjacent blades K, so that when the shed is opened the bar N, together with the 5 comb O, are made to move endwise or laterally in the direction of the arrow P in Fig. 3, the effect of such endwise movement of the said comb being to cause each warp-thread to cross each blade, so as to pass onto the other 10 side thereof, as shown in Fig. 4, and simultaneously with such lateral movement of the bar N the shuttle is sent across the loom and the shed closed, in doing which the pile-forming warp, which has been crossed over the 15 blades, is formed into a loop over each blade, as shown in Fig. 5, the length of warp required to form the loop being drawn off the spools or bobbins G by the oscillating movement of the lever-arms G³, so that when the free ends of 20 the blades are raised, as shown in full line in Fig. 2, the pile-warp, which has just been drawn off the spools by the lever-arms G³, is in a slack condition, and therefore can be drawn up by the upward movement of the 25 blades, so as to lengthen the loop. The crossing of the warp and the introduction of the weft makes the loops secure in the fabric, as will be well understood by those conversant with weaving. It will be understood that by 30 the beating up of the sley toward the breast-beam the newly-formed loops will be carried forward to the extreme point of the triangular blades K and within reach of the oscillating stripping-brush Q which strips the loops from 35 the blades, which at this particular time are elevated, as shown in Fig. 2. The blades K, which are fixed upon the horizontal shaft J, are elevated or caused to rise by means of the said shaft J being made to rock, which is effected by means of lever-arm R and the connecting-rod R' attached to levers R² and R³, the latter of which is oscillated by means of a box-cam 12 on the shaft R⁴. (Shown in light dotted lines of Fig. 1.) A roller 13 engages with 40 the cam 12 and is carried by one end of the lever R³, so that the requisite motion of the blades K may be had. The roller 13 may be removed from the cam, or the parts may be otherwise disconnected when no vertical motion 45 is to be given to the blades K and the blades then remain stationary by gravity, or they may be fastened in any desired position in any convenient manner. Where a short pile or 50 loop is to be formed the blades K do not rise; but it will be understood that any length of loop or pile can be formed by causing the blades to rise to various heights, which is determined by the extent of movement made by the arrangement of cams and levers. The 55 stripping-brush Q is made to reciprocate to and from the points of the blades by means of another cam 14, fixed on the shaft R⁴, (see Fig. 1,) and levers and rods S, S', and S², the latter of which works upon a fulcrum S³, and 60 is connected to the end of a lever-arm S⁴, carrying the brush Q and also a friction guide or bowl a. In order to give the necessary

sweep or combined to-and-fro and up-and-down motion to the brush Q for the purpose of stripping the loops off the blades, a bowl 70 a, carried by lever-arm S⁴, rides or travels up the movable inclined plane b, hinged at c. The bowl then follows down the path or fixed inclined plane d and finally passes underneath the forward end of the said movable inclined 75 plane b, which falls behind to be ready for the next forward movement of lever-arm S⁴, and this goes on at each reciprocatory movement of lever S². The endwise or lateral movement is given to the bar N and comb O 80 by means of bell-crank lever T, (see Fig. 3,) operated by cam T', made to revolve by hooked finger U, connected to lever U', Fig. 2, which is operated at every backward movement of the sley by finger U², attached to sley, coming into contact with the bowl on the upper end of lever U', such movement drawing down the hooked finger U, which engages with a stud on cam T' and rotates it a distance equal to the distance between the studs on 90 said cam. The levers last mentioned are brought back in the opposite direction by means of the spiral spring U³. (See Fig. 3.)

It will be seen that at every revolution (or at every alternate or third revolution, as previously determined) of the crank-shaft the pile-forming warp is passed over the blades and that loops are formed and made secure by the weft, the length of such loops being determined by the depth of the blades. When a longer loop is required than the depth of the blades will allow, the said blades are made to rise after the warp has crossed over them, which is effected by giving a rocking motion to the shaft upon which they are mounted, as previously described. The loops thus made, if required, may be severed by means of a knife formed at the upper end of each blade, or the loops may be severed in any other convenient manner.

By the apparatus above described looped pile rugs, door-mats, imitation-skin rugs, and other pile fabrics can be expeditiously manufactured, and as each loop is interwoven with the fabric it will be found very durable.

We claim as our invention—

1. In a pile-fabric loom, the combination, with a shaft arranged at the middle portion of the warp, of a series of knives projecting from the said shaft in line with the warp and means for oscillating the shaft, whereby the free ends of the said knives are raised vertically and adapted to increase the length of the pile-loops, substantially as set forth.

2. In a pile-fabric loom, the combination, with a series of vertically-oscillating knives arranged in line with the warp, of a vibrating comb arranged crosswise of the warp, whereby the pile-threads are moved laterally over the knives, substantially as set forth.

3. In a pile-fabric loom, the combination, with a series of vertically-oscillating knives arranged in line with the warp, of a reciprocating stripping-brush adapted to remove the

pile-loops from the points of the knives, substantially as set forth.

4. In a pile-fabric loom, the combination, with an oscillatory unwinding device adapted to periodically draw off portions of the pile-warp threads from their spools, of a series of vertically-oscillating knives engaging with the pile-warp threads and adapted to raise the slack portions thus drawn off the spools into loops, substantially as set forth.

5. In a pile-fabric loom, the combination, with the oscillatory knives for raising the pile-loops, of a reciprocating stripping-brush provided with an actuating-lever and a pro-

jecting guide, and inclined planes adapted to control the motion of the said guide, whereby the brush is adapted to remove the loops from the points of the knives, substantially as set forth.

In testimony whereof we affix our signatures in presence of two witnesses.
